UNITED STATES PATENT OFFICE.

JOHN H. CASTONA, OF GULFPORT, MISSISSIPPI.

EXTRACTOR.

1,098,312.

Specification of Letters Patent. Patented May 26, 1914.

Application filed October 9, 1912. Serial No. 724,807.

To all whom it may concern:

Be it known that I, JOHN H. CASTONA, a citizen of the United States, residing at Gulfport, in the county of Harrison and State of Mississippi, have invented new and useful Improvements in Extractors, of which the following is a specification.

This invention relates to turpentine and rosin extractors, and its object is to provide an extractor whereby the natural solvent of the rosin (turpentine) may be utilized for its extraction and the objections incident to the use of high pressure steam and hydro-carbons or other foreign solvents avoided.

A further object of the invention is to provide an extractor whereby the turpentine may be rapidly and economically extracted from the wood and whereby a greater quantity and higher grade of turpentine may be obtained from a given amount of material than by the use of any of the ordinary processes.

The invention consists of the features of construction, combination and arrangement of parts hereinafter fully described and claimed, reference being had to the accompanying drawings, in which:

Figure 1 is a sectional elevation of an extractor embodying my invention. Fig. 2 is a sectional plan view on line 2—2 of Fig. 1. Fig. 3 is a sectional plan view on the line 3—3 of Fig. 1.

Referring to the drawing, 1 designates an outer casing or cylinder having an upper removable head 2 provided with a feed inlet 3, said inlet being normally closed by a hinged door 4 fastened in position by wing bolts 5 provided with clamping nuts 6. Through this inlet 3 the comminuted wood to be treated is fed into the extractor. The door 4 seats against a flange 7, forming a tight joint to prevent escape of the steam and volatile products, which latter upon their liberation from the material discharge through a pipe 8 having a controlling valve 9 to a suitable condenser.

The casing or cylinder 1 is provided with an upper fixed dome-shaped bottom head 10 and a lower removable bottom head 11, which are relatively spaced to form an intervening steam chest or heating chamber 12. The head 11 is provided with a flange 13 which fits frictionally within the lower end of the

casing, thus permitting said head to be removed whenever occasion requires, for access to the interior of said chest or chamber.

Communicating with the chest or chamber 12 through the head 11 is a steam supply pipe 14 having a controlling valve 15, and also communicating with said chamber through said head is an exhaust pipe 16 having a controlling valve 17. The pipe 14 is provided for supplying live steam to heat the chamber 12, while the pipe 16 permits off of any water of condensation, and is also adapted by the opening of the valve 17 to permit of a regulated exhaust of steam therefrom to maintain an even temperature within the chest or chamber. A coupling 18 communicates with the upper portion of the chamber 12 through the head 10 and is in the form of a controlling valve having a stem 19 projecting outwardly through a stuffing box 20, which prevents leakage of vapors to the exterior.

Arranged within the outer casing or cylinder 1 is a perforate cage or basket 21, having a perforate bottom 22, said cage or basket being arranged to rest at its base upon a flange 23 secured to the interior of the casing. This cage or basket is designed to receive the body of comminuted wood to be treated and is disposed in spaced relation to the casing to provide an intervening annular passage 24 for the discharge of the volatile constituents liberated from the wood and free passage of the same to the pipe 8, the liberated rosin gravitating downward through the perforate bottom 22 and entering a collection chamber 25 formed between the same and the head 10.

At its lower end the casing 1 is provided with an outlet 26 communicating with an opening 27 in the cage, through which the body of comminuted wood after treatment may be raked or otherwise discharged from the cage. The outlet or manhole 27 is closed by a door or cover 28 secured in position by swing bolts 29 having clamping nuts 30 and resting against a gasket 31 to maintain a steam and vapor tight joint. A pipe 32 communicates with the chamber 25 for the withdrawal of the rosin and water of condensation from the steam associated therewith, and said pipe is provided with a controlling valve 33.

Extending centrally and longitudinally

within the perforated vertical cage 21 is a 5 perforated steam supply pipe 34 closed at its upper end in any suitable manner, as by a plug 35, and communicating at its lower end with the valve 18, through which steam may be supplied to the pipe 34 from the steam chest or chamber, which is supplied with steam through the pipe 14. When the cage is filled with a body of comminuted 10 wood, the valves 15, 17 and 18 are opened, whereupon steam flows into the chamber 12 and to the pipe 34 and is distributed by the latter to and throughout the mass of wood, thereby evenly and positively heating the 15 wood and quickly driving off the volatile constituents. The perforations in the cage 21 and the discharge space 24 permit of the rapid discharge of the liberated volatile vapors, and the liberation thereof under a 20 moderate degree of steam heat and pressure, thus permitting the turpentine to pass off to the condenser and to be liquefied without unduly heating or holding the same in vaporous condition long enough to separate any 25 of its lighter volatile constituents into uncondensable gases. By this means a thorough extraction of the valuable products from the wood is insured, and also the discharge and recovery of a maximum amount 30 of turpentine, including that portion thereof normally remaining unextracted and that portion thereof often evolved into uncondensable gases under ordinary processes.

Located within the chest 12 is a heating 35 coil 36 communicating with a solvent supply pipe 37 having a controlling valve 38, and arranged within the top of the extractor is a perforated spray coil 39 communicating with the coil 36 through a pipe 40 having a 40 controlling valve 41. Through the pipe 37 the solvent preferably used, namely turpentine, may be supplied to the coil 39 and preliminarily heated to a low degree by the coil 36, so that the solvent may be discharged in 45 the top of the cage and allowed to percolate throughout the mass of the comminuted wood to leach out the rosin and increase its fluidity and facilitate its discharge into the chamber 25. The solvent may be withdrawn 50 from the rosin through the pipe 32 and separated therefrom, or may be evaporated by the heat and discharged through the pipe 8 to the condenser, from which it will be understood that a store of turpentine may be 55 used rapidly and recovered for further use after each extraction. The steam chamber 12 serves to heat the bottom of the extractor casing to retard and reduce condensation of the steam injected through the pipe 60 34, to heat and maintain the rosin in the chamber 25 in a fluid state for ready discharge, and to heat the turpentine solvent on its passage to the spray coil 39. By this 65 means the necessity of heating the solvent in tanks before introducing it to the extract-

or is avoided, thus preventing the losses occasioned by keeping a body of solvent in bulk heated any material length of time.

In operation, after the perforated cage is filled with comminuted wood, and the extractor sealed, heated turpentine is supplied through the perforated coil 39 to initially extract the rosin while the mass of wood is being heated by means of the steam injected through the pipe 34. After the greater 70 portion of the rosin has been extracted, the valves 38 and 40 are closed to cut off the feed of the solvent, while the injection of steam through the pipe 34 is continued until the volatile constituents and remainder of 75 the rosin are fully extracted from the wood, the steam and volatile constituents passing off through the pipe 8 to the condenser, from which the turpentine may be run off into receiving tanks for storage. The rosin is then 80 drawn off and the cage emptied and refilled, 85 whereupon the operation above described is repeated.

It will be seen from the foregoing description that by means of the extractor herein disclosed turpentine may be used as a solvent for extracting the rosin, thus avoiding the use of hydro-carbons and other solvents which contaminate the products and are separated with difficulty therefrom, and that 90 by the use of a perforated cage in spaced relation to the casing and the arrangement of the perforated steam supply pipe 34 therein, the steam employed for heating the mass of 95 comminuted wood is thoroughly and evenly distributed throughout the same, thus insuring rapidity of extraction and free discharge 100 of the vapors and rosin, as well as expansion of steam throughout the mass. By this means the use of steam under great heat and 105 pressure, such as required when the source of steam supply is arranged below the cage, is avoided, as well as the injurious action thereof upon the turpentine vapors. The 110 construction of the extractor permits of the discharge of the volatile products as soon as liberated, thus avoiding undue condensation of the steam in the mass of wood and undue or prolonged heating of the turpentine vapors, tending to convert the lighter 115 vapors thereof into uncondensable gases. The larger amount of turpentine in a high state of purity may, therefore, be obtained from a given amount of wood, with greater 120 economy of operation and the advantage of obtaining products which are salable at a higher price. The construction described also permits of the extractor being readily repaired, cleaned, filled and emptied, as will be understood from the foregoing description.

I claim:—

1. An extractor comprising an outer inclosing casing, said casing being provided with an extracting chamber, a heating chamber 125

at the base of the casing below said extracting chamber and closed against communication therewith, and a rosin collection chamber between said extracting and heating chambers, a perforated inner receptacle disposed within the extracting chamber, said receptacle being spaced at its sides from the casing to provide a surrounding vapor outlet and being in communication with said 5 rosin collection chamber and through its perforations at all levels in communication with the vapor collection space, means for supplying steam to the heating chamber, a perforated steam injection pipe communicating 10 with the heating chamber and extending centrally and upwardly through the perforated receptacle to the top thereof, a solvent supply pipe, a solvent heating coil communicating with said pipe and disposed 15 within the heating chamber, a solvent discharge coil communicating with the top of the perforated receptacle, and a conducting connection between said solvent heating coil and solvent discharge coil.

20 2. An extractor comprising an outer inclosing casing having a valved vapor discharge outlet at its top, a heating chamber at its bottom and a rosin collection chamber above said heating chamber, said collection chamber being provided with a valved outlet, a perforated cage arranged within the casing above said collection chamber and in spaced relation to the casing, a perforated steam injection pipe disposed 25 within the chamber, a solvent injector within the top of the cage, a heating coil within the heating chamber, said coil being in communication with said injector, means for

supplying steam to the heating chamber, and means for supplying a solvent to the coil for delivery to the injector.

3. An extractor comprising an outer inclosing casing having a valved vapor discharge outlet at its top and a refuse outlet at a point above its bottom, a dome-shaped partition between the bottom of the casing and said outlet, said partition forming a heating chamber closed against communication with the casing, a second perforated partition arranged above said dome-shaped partition and providing therewith a rosin collection space, a valved rosin discharge outlet leading from said space steam supply and exhaust pipes communicating with the heating chamber, a perforated cage arranged within the casing and supported by said perforated partition in spaced relation to the casing, said cage being in communication with said refuse outlet, a perforated steam supply pipe communicating at its lower end 60 with the steam supply chamber and extending axially through the cage to a point at or near the top thereof, a valve controlling the flow of steam to said perforated pipe from the heating chamber, a solvent spray coil disposed within the top of the cage, a heating coil disposed within the heating chamber, a solvent conducting pipe connecting said coils, and a solvent supply pipe connected with the latter named coil.

70 In testimony whereof I affix my signature in presence of two witnesses.

JOHN H. CASTONA.
